UNITED STATES PATENT OFFICE.

GEORGE JACOBS, OF DETROIT, MICHIGAN.

MIXING DEVICE.

1,275,036.

Specification of Letters Patent. Patented Aug. 6, 1918.

Application filed December 18, 1916. Serial No. 136,630.

To all whom it may concern:

Be it known that I, GEORGE JACOBS, a citizen of the United States of America, residing at Detroit, in the county of Wayne and State of Michigan, have invented certain new and useful Improvements in Mixing Devices, of which the following is a specification, reference being had therein to the accompanying drawings.

10 This invention relates to a mixing device that may be utilized for carbureting, atomizing and vaporizing purposes.

The primary object of my invention is to provide positive and reliable means, in a manner as hereinafter set forth for causing an admixture of liquid and fluids by centrifugal force, thus insuring an intimate commingling of liquid and fluid molecules and the production of an admixture that is highly efficient for the purposes for which it is intended. By using the centrifugal force as a mixing medium or agent, such liquid, as gasoline or kerosene may be vaporized or broken up to that extent that the molecules thereof may be impregnated or intimately mixed with air or other fluid. Provision has been made in connection with the device so that the air or fluid used thereby may be laden with moisture, and this is accomplished by using a humidifier through which air is forced into a mixing chamber, where with the centrifugal force produced therein, the mixture is more or less compressed and will provide a constant and uniform supply. For instance, when the device is utilized as a carburetor for an internal combustion engine, the intake manifold of the engine is constantly charged with an explosive mixture under compression, so that immediately upon the intake valves of the engine being opened, the explosive mixture enters the cylinders of the engine and does not depend on suction or a reduction of pressure in the cylinders to charge the same.

15 A further object of my invention is to provide a mixing device wherein the parts are constructed with a view of reducing the cost of manufacture and at the same time retain those features by which safety, durability, ready control, and applicability to various uses are secured. With such ends in view, my invention resides in the novel construction, combination and arrangement

of parts to be hereinafter specifically described and then claimed.

Reference will now be had to the drawings, wherein—

Figure 1 is a front elevation of the mixing device, partly broken away and partly in section;

Fig. 2 is a detail view of a portion of a rotary mixer;

Fig. 3 is a vertical longitudinal sectional view of the device, and

Fig. 4 is a detail view of one of the elements of the humidifier.

In describing my invention by aid of the views above referred to, I desire to point out that the same are intended as merely illustrative of an example by which my invention may be put into practice, and I do not care to confine myself to the precise construction and arrangement of parts shown. The following description is therefore to be broadly construed as including such substitute constructions and arrangement of parts which are the obvious equivalent of those to be hereinafter referred to.

20 In the drawings, 1 denotes a humidifier that is somewhat inverted U-shaped and has lower open ends in communication with a tank or reservoir 2. The shape of the humidifier structure 1 provides a central compartment 3 and the front of the humidifier structure is closed by the rear wall 4 of the mixing chamber 5 suitably connected to the humidifier structure. The mixture chamber 5 is circular in elevation and has a detachable front wall 6 provided with a central bearing 7.

25 The greater part of the rear of the humidifier structure 1 is open and in communication with a cylindrical fan casing 8. Adjacent this fan casing is a power transmission casing 9 affording a bearing in alignment with the bearing 7 of the detachable front wall 6.

30 Journalized in the bearing of the casing 9 and the bearing 7 of the detachable front wall 6 is a tubular shaft 10 and mounted on this shaft within the fan casing 8, is the hub 11 of a fan 12. Abutting the hub 11 of the fan 12 is the long hub 13 of a rotary mixing device within the mixing chamber 5, said device having radial blades 14 that are 35 curved from the inner ends thereof to the

outer ends and are dished or convexo-concave in cross section. The upper ends of the blades 14 are in proximity to the inner annular wall of the mixing chamber 5 and a central opening 15 in the wall 4 provides clearance for the long hub 13 of the mixing device and at the same time provides an air inlet opening into the mixing chamber. The air inlet opening 15 communicates with the central compartment 3 of the humidifier 1 and the passage of air through said opening is controlled by a disk shaped valvular member 16, carried by the end of a slide sleeve 17 on the long hub 13 of the mixing device. The sleeve 17 has apertured ears 18 and pivotally connected thereto is a lever 19 extending through an opening 20 provided therefor in a U-shaped partition 21 within the central compartment 3. The lever 19 is pivotally held adjacent the opening 20, as at 22 and the lower end thereof is pivotally connected to a rod 23 extending through a gland and stuffing box 24 carried by the tank or reservoir 2. By reciprocating the rod 23 the valvular member 16 may be moved to and from the opening 15 and thus control the amount of air entering the mixing chamber.

The end of the tubular shaft 10 journaled in the bearing 7 is closed by a plug 24 and the inner end of said plug has a stationary needle valve 25, while the outer end of said plug is inclosed by a cap 26 connected to the bearing 7 or the detachable front wall 6. Movable to and from the stationary needle valve 25 is a reciprocable tubular valve member 27 that protrudes from that end of the tubular shaft journaled in the power transmission casing 9. The casing 9 has a bracket 40 or bearing 28 as a fulcrum for a lever 29 and said lever has the upper end thereof operatively connected to the tubular valve member 27 so as to reciprocate the same. A rod 30 may be connected to the lower end of the lever 29 to facilitate operating the same from a remote point.

Connected to the tubular valve member 27 is a hose or flexible connection 31 in communication with a supply tank 32 adapted to contain a fuel that may be vaporized, as gasolene or kerosene. The liquid may flow by gravity into the tubular valve member 27 and for distributing the liquid in the mixing chamber 5 the tubular shaft 10, adjacent the needle valve 25, has radially disposed discharge members 33 and as best shown in Fig. 3, the outer ends of said discharge members are funnel shaped or flared. The members 33 extend through some of the blades 14 and are adapted to discharge gasolene toward the inner walls of the mixing chamber 5.

Any suitable power transmission may be located within the casing 9 to rotate the tubular shaft 10, and as shown there is a

gear wheel 34 which when revolved, rotates the tubular shaft 10, and places the fan 12 in operation, also the rotary mixing device. Since the members 33 are carried by the tubular shaft 10, the gasolene admitted to said member will be forcibly discharged by centrifugal force and in this manner vaporized on entering the mixing chamber.

In the humidifier 1 there are a series of baffle plates or members supported in staggered relation transversely of the humidifier by the side and central walls of said humidifier, as shown in section in Fig. 1. The baffle members provide a sinuous, tortuous, circuitous or staggered path for air from the fan casing 8, also for a liquid, as water, that is supplied to the humidifier 1 by a connection 35. The elements arranged within the humidifier 1 are designated 36 and water drips upon the uppermost elements to gradually flow over the same into the tank or reservoir 2. Air passing between the elements will be laden with moisture and the moisture will be drawn into the mixing chamber.

By regulating the supply of water to the humidifier 1, the amount of moisture carried into the mixing chamber may be varied, so that the final mixture will have a degree of moisture which is desirable, particularly in connection with an explosive mixture, to prevent the accumulation of carbon and other deposits in and about an engine cylinder.

The mixing chamber 5 has a peripheral channel 37 that gradually increases in cross sectional area to an outlet connection 38, and when the mixing device is used as a carbureter in connection with an internal combustion engine, the outlet connection 38 is connected to the intake manifold or intake chamber of the engine.

In operation, the valvular members 16 and 27 control the admission of liquid and fluid, as gasolene and air, to the mixing chamber 5, and with the mixing device rotating in said chamber, it is apparent that the moisture laden air is forcibly drawn into the chamber. Since the members 33 are carried by the mixing device, the gasolene is discharged by centrifugal force and is vaporized to that extent that particles thereof can intimately commingle with the air in the mixing chamber. A thorough mixture is assured by the rotary mixing device and this device will tend to compress the mixture in the outlet connection 38 and a manifold or chamber to which it may be connected.

What I claim is:

1. A mixing device comprising a chamber, a humidifier having a water supply connection, a tubular shaft axially of said chamber, a fan on said shaft adapted to force air through said humidifier into said chamber, a rotary mixing device carried by said

shaft within said chamber, members carried by said mixing device, means extending through said tubular shaft adapted to supply a liquid to said members.

5 2. A device of the type described comprising a mixing chamber having an outlet connection, a humidifier having a water supply connection, a tubular shaft extending through said humidifier into said mixing chamber, a fan on said shaft adapted to force air through said humidifier into said mixing chamber, means extending through said tubular shaft adapted to admit liquid to said mixing chamber, and means carried by said shaft within said mixing chamber 10 adapted to discharge the liquid by centrifugal force to commingle with the air in said casing.

15 3. A device of the type described comprising a humidifier having a water supply connection, a mixing chamber carried thereby and in communication with said humidifier, a tubular shaft extending through said humidifier into said mixing chamber, a fan on said shaft adapted to force air through said humidifier into the mixing chamber, means in connection with said humidifier for saturating the air that passes through the humidifier with moisture, means for conducting a supply of liquid through said shaft into said mixing chamber, a mixing device on said shaft within said chamber,

and members carried by said shaft adapted to discharge liquid in said chamber by centrifugal force.

35 4. A device of the type described comprising a humidifier, a mixing chamber connected thereto, a tubular shaft extending through said humidifier into said mixing chamber, a fan on said shaft adapted to force air through said humidifier into said mixing chamber, means in connection with said humidifier adapted to saturate the air passing therethrough with moisture, a mixing device on said shaft within said mixing chamber and having curved blades extending in proximity to the annular wall of said mixing chamber, members carried by said shaft extending through the blades of said mixing device and adapted to discharge 40 liquid in said chamber by centrifugal force, a needle valve in said shaft, a tubular reciprocable valve member adapted to supply and control the admission of liquid to said members, and means in said humidifier movable to and from said mixing chamber adapted to control the admission of moisture saturated air thereto.

45 In testimony whereof I aff. my signature
in the presence of two witnesses.
